VIBRATORY MASSAGER ATTACHMENT FOR A SUCTION CLEANER

Eugene F. Martinec, East Cleveland, Ohio, assignor to Health-Mor, Inc., Chicago, Ill., a corporation of Illinois

Filed Aug. 30, 1960, Ser. No. 61,951

Term of patent 14 years

(Cl. D83—1)

FIG. 1 is a front elevation of a vibratory massager attachment for a suction cleaner, illustrating my new design;

FIG. 2 is a side elevation thereof;

FIG. 3 is a top plan view thereof;

FIG. 4 is a rear elevation thereof; and

FIG. 5 is a bottom plan view thereof.

I claim:

The ornamental design for a vibratory massager attachment for a suction cleaner, substantially as shown.
